UNITED STATES PATENT OFFICE.

DALL WORTHINGTON AND CHRISTIAN PETERSEN, OF BALTIMORE, MARYLAND, ASSIGNORS TO THEMSELVES AND DIVEN BROTHERS & CO., OF SAME PLACE.

ROTARY PLOW.

SPECIFICATION forming part of Letters Patent No. 633,770, dated September 26, 1899.

Application filed October 15, 1898. Serial No. 693,610. (No model.)

To all whom it may concern:

Be it known that we, DALL WORTHINGTON and CHRISTIAN PETERSEN, citizens of the United States, residing at Baltimore, in the 5 State of Maryland, have invented certain new and useful Improvements in Rotary Plows, of which the following is a specification.

This invention relates to a revoluble plow for plowing land.

10 The object of the invention is to provide a land-plow having a rotary head with a plural number of spades and mounted on a carriage to be drawn by horses or other power.

15 The invention is illustrated in the accompanying drawings, in which—

Figure 1 is a top plan view of the plow. Fig. 2 is a side elevation of the plow. Fig. 3 shows two views in detail of the pawl-and-ratchet device on one of the wheels. Fig. 4 is a front elevation of the plow and in full lines shows the position of the plow when cutting a furrow and in broken lines shows the raised position the plow takes when it is out of the ground. Fig. 5 is a perspective view of the 25 shell or cylinder of the plow and shows how the spades are attached.

The rotary plow proper, A, comprises a wheel-head a, (see Figs. 1 and 2,) on which is secured a circular-shaped cylinder or shell 30 B, having a zigzag-rim formation. (Shown in Figs. 2 and 5.) One face c of each zigzag is broader than the other face c'. The broad face has bolt-holes d. There may be any desired number of zigzags. In the present instance there are sixteen. The spades e are flat steel plates having a cutting edge e', which cuts into the earth, and bolt-holes. One spade is secured on the broad face of each zigzag by bolts d'.

40 While the flat side of each spade is in contact with the broad face c of one zigzag the heel or edge of the spade rests or abuts against the narrow face c' of the next adjoining zigzag. By this construction the spades are 45 firmly seated and the strain on the bolts d' is minimized, and all the spades project tangentially. Another result of this construction of cylinder or shell B with the zigzag-rim formation and flat metal plates e in tangential planes 50 is that a space or pocket is formed between

every two adjoining metal plates e, into which pocket the earth cut by the plate enters, said earth being carried completely over by the rotation of the plow and dumped behind, as hereinafter set forth. 55

The rotary plow A is secured rigidly on the end of a pivoted shaft F, the said pivoting allowing the end of the shaft to which the plow A is attached to be raised and lowered, as indicated in Fig. 4. The end of the shaft 60 F has on it a knob or ball, (indicated in Figs. 1 and 4,) and this ball fits in a socket on a suitable bearing or hanger G, which is attached to a horizontal frame H, supported on an axle or shaft I, mounted on running wheels J. A 65 pole f is attached to the frame, and the design is to have the machine drawn by horses.

It will be seen the end of the shaft F which carries the rotary plow projects at the side of the machine beyond the running wheel J and 70 that therefore the rotary plow A has position outside of or beyond the said running wheel, which supports the machine.

A well-known pawl-and-ratchet device is provided where each running wheel connects 75 with the axle or shaft to make a rigid connection between the wheel and axle when the machine is drawn forward. Thereby the rotation of the running wheels J causes the axle or shaft also to rotate; but when the machine 80 is backed the wheels only will rotate. This pawl and ratchet is shown in Fig. 3. A collar g is rigid on the axle I, and a pawl h is pivoted on the collar and pressed by a spring h'. The hub of the wheel J has a circular recess i, and ratchet-teeth i' are around the internal rim of said recess, and the pawl h, carried by the axle, engages these ratchet-teeth 85 when the machine is drawn forward; but said pawl slips over the teeth whenever the machine is backed. 90

The free end of the pivoted plow-shaft F is carried at the end of an arm L, whose other end is pivoted on the end of the axle I, which projects outside of the wheel J. This arm 95 acts as a brace and carrier. The free end and the rotary plow A are raised and lowered by an angle-lever N, pivoted at k to the frame H. The short arm l of the angle-lever is connected with the pivoted shaft F by means 100

of a link m . By grasping the handle of the long arm of the lever N the pivoted shaft and plow A may be raised and lowered.

Provision is made to retain the plow at the 5 raised position. This consists of a segment-rack n , fixed on the frame H , and a pawl o and operating-lever o' , attached to the angle-lever N .

The gearing or power-transmitting mechanism 10 comprises a drive-gear wheel p on the axle I and engaging a pinion q on a cross-shaft mounted on the frame. This cross-shaft carries a sprocket-wheel r , and a smaller sprocket r' is attached to a sleeve r^2 , loose on 15 the axle, while a chain s connects the two. A larger sprocket t is also fixed on the loose sleeve r^2 , and a chain t' connects therefrom with a smaller sprocket t^2 on the pivoted shaft F . It will be seen that the transmission-gear 20 is arranged to impart speed to the plow-shaft F .

The action of the plow will be understood by reference to Fig. 2. The ground-surface is indicated by the line u and the depth of 25 the furrow cut by the rotary plow by the line v . As the earth is cut by the spades e on their upward movement it will be carried over the plow and dumped behind it.

Having thus described our invention, what 30 we claim as new, and desire to secure by Letters Patent of the United States, is—

1. A rotary plow having a circular-shaped cylinder or shell provided on its rim with zig-zag formations, and spade-plates each of 35 which is secured with its broad side on a face of one zigzag and with its heel abutting against a face of the next zigzag, whereby a space or pocket to receive earth is formed between every two adjoining spade-plates.

2. In a rotary-plow machine the combination of a frame; an axle and running wheels carrying the frame; a revoluble shaft having one end projecting at the side of the machine beyond the running wheel, said shaft being 45 movable up and down at one end only; and a rotary plow mounted on the said projected end of the revoluble shaft.

3. In a rotary-plow machine the combina-

tion of a frame mounted on running wheels; a revoluble shaft pivoted so that one end shall 50 be free to be raised and lowered; a rotary plow mounted on the free end of said shaft and having position outside of or beyond the said running wheel; and a brace and carrier-arm attached to the free end of the said revoluble shaft.

4. In a rotary-plow machine the combination of a frame; a revoluble shaft pivoted so that one end shall be free to be raised and lowered; a rotary plow mounted on the free 60 end of said shaft; a brace and carrier-arm attached to the free end of the said revoluble shaft; and a lever for raising and lowering the said shaft and plow.

5. In a rotary-plow machine the combination of a frame; an axle and running wheels and a gear-wheel, p , on the axle; a sleeve loose on the axle and carrying two gear-wheels; a cross-shaft having two wheels, q , and, r , one connected with the said gear-wheel on the 70 axle and the other with one of the wheels on the loose sleeve; a revoluble shaft, F , having a wheel, t^2 , connected with the other wheel on the said sleeve; and a rotary plow connected with said shaft, F , and having position outside of or beyond the said running wheel.

6. The combination of a frame mounted on an axle and running wheels; a rotary plow carried by said frame and having peripheral 80 spades which form a space or pocket between every two adjoining spades; and gearing transmitting motion from the axle or wheels to said plow whereby the plow will rotate only in a direction opposite that in 85 which the said running wheels turn and the earth cut by the spades will be carried completely over and dumped behind the rotary plow.

In testimony whereof we affix our signatures in the presence of two witnesses.

DALL WORTHINGTON.
CHRISTIAN PETERSEN.
